Primary Examiner—Cathy Anne MacCormac*Attorney, Agent, or Firm*—Lyon & Lyon[57] **CLAIM**

The ornamental design for a chew toy for dogs, as shown and described.

DESCRIPTION

FIG. 1 is a front elevational view of a chew toy for dogs showing my new design which is symmetrical about its central axis such that the rear, top and bottom views would all be identical to FIG. 1; and,

FIG. 2 is an end view thereof taken from the right side of FIG. 1 which is identical to an end view taken from the left side of FIG. 1.

1 Claim, 1 Drawing SheetFIG. 1

FIG. 2
